UNITED STATES PATENT OFFICE.

JOHN G. BALING, OF BALTIMORE, MARYLAND.

RAIL-JOINT.

1,118,620.

Specification of Letters Patent. Patented Nov. 24, 1914.

Application filed January 20, 1914. Serial No. 813,227.

To all whom it may concern:

Be it known that I, JOHN G. BALING, citizen of the United States, residing at Baltimore, in the State of Maryland, have invented certain new and useful Improvements in Rail-Joints, of which the following is a specification.

This invention relates to rail joints, and has for its object the provision of a strong, durable and comparatively simple connecting means for securely uniting the abutting ends of railway rails, whereby a practically smooth continuous tread surface may be produced at the junction of the rail ends and pounding and hammering of the said rails, incident to the passage of rolling stock thereover, reduced to a minimum.

A further object of the invention is to provide a rail joint the construction of which is such that should any one rail in a line of track become broken or otherwise damaged, said damaged rail may be readily removed from the cross ties for repairs or renewal without disturbing the alinement of the adjacent rails.

A further object is to provide a joint which will effectually unite the abutting ends of standard rails without the necessity of materially altering the construction thereof.

A further object is to provide means for preventing lateral spreading of the rails, and means for reinforcing said rails at the junction thereof.

A still further object is to generally improve this class of devices so as to increase their utility, durability and efficiency.

Further objects and advantages will appear in the following description, it being understood that various changes in form, proportions and minor details of construction may be resorted to within the scope of the appended claims.

In the drawings:—Figure 1 is a perspective view of a rail joint constructed in accordance with the present invention; Fig. 2 is a transverse sectional view taken on the line 2—2 of Fig. 1, and looking in the direction of the arrow; Fig. 3 is a similar view taken on the line 3—3 of Fig. 1, and looking in the direction of the arrow; Fig. 4 is a perspective view of the several parts comprising the rail joint detached; and Fig. 5 is a perspective view illustrating a modified form of the invention.

Corresponding and like parts are referred to in the following description and indicated in all the views of the accompanying drawings by the same reference characters.

The improved rail joint forming the subject-matter of the present invention is principally designed for connecting the abutting ends of adjacent rail sections, and by way of illustration is shown applied to a section of track in which 5 designates the cross ties and 6 the rails. The opposite sides of the head 7 of each rail at the inner end thereof are cut-away even with the web of the rail to form a reduced extension 8 adapted to aline with the extension of a mating rail when said rails are assembled, as best shown in Fig. 1 of the drawings. Spanning the rail ends at the junction thereof is a chair including a base plate 9 having oppositely disposed upstanding side pieces 10 and 11, one of which is preferably formed integral with the base piece 9, while the other, namely the side piece 11, is detachably secured to said base so as to permit the ready removal of any particular rail for repairs or renewal without in any wise disturbing the alinement of the adjacent rails. The detachable side piece 11 of the chair is preferably provided with a depending longitudinally disposed lip 12 which bears against the upper face of the base 9 and is provided with spaced notches 13 for the reception of spikes or similar fastening devices 14, there being corresponding spikes 15 bearing against the side piece 10 for securing the chair, together with the rails, in position on the adjacent cross tie. The cross tie 5 is preferably formed with a seating recess 16 adapted to receive the adjacent chair so as to assist in properly alining the chairs on the cross ties, and also to prevent lateral spreading of the rails. The heads 7 of the rail ends at their junction with the reduced extensions 8 are preferably curved laterally to form shoulders 17, while the opposite ends of the side pieces 10 and 11 are correspondingly curved, as indicated at 18, for engagement with said shoulders. The curved faces or shoulders 17 not only serve to reinforce and strengthen the extensions 8 at their junction with the rail heads 7, but in conjunction with the curved faces 18 form in effect a lap-joint and serve to assist in preventing battering of the rail ends, as well as to reduce pounding and hammering of the rails incident to 110

the passage of rolling stock thereover. The side pieces 10 and 11 are preferably of the same thickness as the cut-away portions of the heads 7 of the rails so that when the 5 parts are assembled the side pieces 10 and 11 will bear against the webs 19 of the rail ends and in which position the upper longitudinal edges 20 of the side pieces will be disposed entirely within the lines of the 10 outer longitudinal edges of the heads 7 of the rails so as to form in effect a smooth continuous rail, and thus prevent pounding and hammering of said rails and flattening of the car wheels.

15 The webs 19 of the rail ends are preferably provided with elongated slots 21 which register with openings 22 formed in the side pieces 10 and 11 of the chair to permit the passage of bolts 23, the latter having 20 their ends threaded in the usual manner for engagement with clamping nuts 24. The opposite ends of the side pieces 10 and 11 are preferably continued longitudinally beyond the curved faces 18 to form extensions 25 which extend beneath and bear against the lower faces of the heads 7 at the shoulders 17 and serve the dual function of reinforcing the webs and heads and as a means for centering the side pieces on the rail ends.

25 It will here be noted that the inner face 26 of each rail end is straight and extends in a vertical plane from the base 27 of the rail to the cut-away portion of the head thereof, so that when the rails are assembled 30 on the cross ties, the webs will be practically continuous and thereby materially strengthen the joint. Such a construction also permits the ordinary standard rail to be employed without the necessity of materially changing the construction thereof, 35 it being merely necessary to remove a portion of the opposite sides of the head of each rail at the inner end thereof to effect the union of mating rails, as will be readily understood. It will further be noted that 40 the inner faces 26 of the rail ends at their junction with the upper edges of the extension 8 are curved, as at 28, while the ends of the side pieces 10 and 11, as well 45 as the curved walls or shoulders 17, are also preferably curved or beveled to assist in preventing damage to the rails by contact with the wheels of a train or locomotive.

50 Should one of the rails become broken or otherwise damaged, it is merely necessary to withdraw the spikes 14 and release the bolts 23, when the detachable side piece 11 of the chair may be lifted off of the base 9 to permit the removal of the damaged rail section. The vertical walls of the seating recesses 16 in the cross ties by engagement 55 with the outer faces of the lips 12 of the detachable side pieces 11 serve to assist in holding said side pieces in position on the 60 rails.

In Fig. 5 of the drawings, there has been illustrated a modified form of the invention, in which the longitudinal extensions 25 on the side pieces are dispensed with and the heads of the rails, instead of being 70 formed with curved shoulders, as shown in Fig. 1, are provided with square shoulders 29. In this form of the device, the side pieces 10' and 11' are preferably cast or otherwise formed integral with the base 75 plate 9', and the rail ends inserted in the chair from the opposite ends thereof. When this form of joint is used, and it is desired to remove a broken rail, it is merely necessary to saw through the side pieces at the 80 juncture of the rails when the broken rail section may be removed from the cross tie. When replacing a broken rail, however, the sectional chair shown in Fig. 1 is preferably used.

85 While it is preferred to position the chairs on the cross ties so that the joint will be disposed between two of said ties, it will, of course, be understood that the joint may be arranged on the cross ties with the joint directly over any particular cross tie, if desired. By such a construction, not only is a practically continuous rail produced and pounding and hammering on the rail ends reduced to a minimum, but the cost of installation and maintenance is also reduced to a minimum.

90 What is claimed is:—

1. A rail joint including mating rails each 100 having the opposite sides of its head cut-away to form reduced extensions of the same width as the webs of the rails, the inner ends of said rails being solid and the faces thereof extended upwardly in a straight line from the bases of the rails to 105 the upper longitudinal edges of the extensions, there being shoulders formed at the junction of the heads with the extensions and curved portions formed at the junction of the vertical faces of the rails with the upper longitudinal edges of the extensions, a chair spanning and junction of the rails and provided with spaced upstanding side pieces fitting within the cut-away portions of the rails and bearing against the reduced 110 extensions thereof, one of said side pieces being detachably secured to the base of the chair and the opposite ends of both side pieces conforming to and adapted to bear against the shoulders of the rails, and fastening devices extending through the extensions and the side pieces of the chair.

115 2. The combination with spaced cross ties having seating recesses formed in the upper faces thereof, of a chair seated in said recesses 120 and provided with spaced upstanding side pieces, one of which is formed integral with the base of the chair and the other detachably secured thereto, rail sections seated within the chair and each having the oppo- 125 130

site sides of its head cut-away to form a reduced extension adapted to bear against the adjacent side pieces of the chair, fastening devices extending through the reduced extensions and side pieces of the chair, and fastening devices engaging the ties and bearing against the lower portions of the side pieces for securing the chair in position on the cross ties.

10 3. The combination with spaced cross ties having seating recesses formed in the upper faces thereof, of a chair seated in said recesses and provided with spaced upstanding side pieces one of which is formed integral with the base of the chair and the other provided at its lower portion with a depending longitudinally disposed lip, the lower face of which rests on the base of the

chair and the outer edge thereof, against the adjacent wall of the recess, rail sections 20 seated within the chair and each having the opposite sides of its head cut-away to form a reduced extension adapted to bear against the adjacent side pieces of the chair, fastening devices extending through the side 25 pieces and the extensions of the rails, and other fastening devices bearing against the lower portions of the side pieces and engaging the adjacent cross tie.

In testimony whereof I affix my signature 30 in presence of two witnesses.

JOHN G. BALING. [L.s.]
